UNITED STATES PATENT OFFICE.

WILLIAM C. ANDERSON, OF TOLEDO, OHIO, ASSIGNOR TO THE LIBBEY GLASS COMPANY, OF SAME PLACE.

DESIGN FOR A CUT-GLASS DISH.

SPECIFICATION forming part of Design No. 22,433, dated May 9, 1893.

Application filed April 13, 1893. Serial No. 470,249. Term of patent 7 years.

To all whom it may concern:

Be it known that I, WILLIAM C. ANDERSON, of Toledo, county of Lucas, and State of Ohio, have invented a certain new and original Design in Cut-Glass Dishes; and I do hereby declare that the following is a full, clear, and exact description thereof, which will enable others skilled in the art to which it appertains to make and use the same, reference being had to the accompanying drawings, and to the numerals of reference marked thereon, which form part of this specification.

My invention relates to a design for cut glass dishes and pertains to the exterior surface ornamentation thereof.

The leading feature of my design is a peripheral row of kite shaped fields in which is formed a checkering with an inner row of kite shaped fields, alternating in their radial arrangement and formed with a checkering.

In the drawings: Figure 1 is a plan view of a dish embellished with my design. Fig. 2 is a transverse sectional elevation.

The center of the dish is laid out with an

octagonal field 1 with kite shaped checkering 2 upon each square of the octagon, there being a concentric row of kite shaped fields 3 in which is a checkering 4 and an outer row of prisms 5 in fan shape, each prism radiating to a common center 6, and intermediate 30 prism 7 curved in opposite directions with a row of prismatic studs 8 between each field 3.

The rays of light reflected from the radial prisms surrounding the upper portion of the dish are refracted by the prismatic checkerings of the kite shaped portions, and the prismatic studs, producing a pleasing effect.

What I claim is—

The design for a cut glass dish as herein shown and described.

In testimony that I claim the foregoing as my own I hereby affix my signature in presence of two witnesses.

WILLIAM C. ANDERSON.
